UNITED STATES PATENT OFFICE.

ROBERT WEISS, OF KINGERSHEIM, GERMANY.

BLEACHING APPARATUS.

1,086,941.

Specification of Letters Patent. Patented Aug. 27, 1912.

Original application filed July 17, 1908, Serial No. 444,011. Divided and this application filed September 29, 1909. Serial No. 520,116.

To all whom it may concern:

Be it known that I, ROBERT WEISS, chemist, a citizen of the Swiss Republic, and resident of Kingersheim, Alsace-Lorraine, Germany, have invented new and useful Improvements in Bleaching Apparatus, of which the following is a full, clear, and exact specification.

My invention, which is a division of U. S. Letters Patent 986,332, granted to me March 7, 1911, relates to an apparatus for treating textile materials, and more especially, for boiling, washing and bleaching them with a bath flowing in a reversible circuit, the said apparatus being designed to accelerate the process when compared with similar processes at present in use, as regards the time occupied, and to simplify and cheapen it as regards completeness, and expenditure upon fuel and chemicals.

According to my invention the apparatus comprises two treating vessels each designed to be charged with textile material to be treated by a liquid bath of an amount but little more than that corresponding to the capacity of one vessel, a pump for maintaining said liquid bath in a circulating motion, connections between said pump and the lower part of said vessels, means for reversing the direction of flow of the liquid bath through the vessels, and an upper intermediate vessel placed between the said treating vessels and connected with the upper part thereof, the whole being arranged in such a manner as to allow of impregnating the material in one of the vessels in full bath under pressure substantially in a direction from below to above and simultaneously treating the material in the other vessel by a kind of dripping or filtering action, and then interchanging these two kinds of treatment by operating said reversing means. Furthermore the two treating vessels are so provided with overflow pipes, and these again with retaining valves, that for the pressure period in one vessel the overflow pipe belonging to it has its retaining valve closed, while simultaneously for the suction period in the other treating vessel the corresponding retaining valve opened in order to allow the excess of liquid in this vessel resulting from an insufficient percolation of the liquid through the material to flow away through the corresponding overflow pipe without affecting the circulation.

Figure 1 of the diagrammatic drawing illustrates the preferred form of this apparatus, it being supposed that it is being employed with a treating liquid heated above 100° C., both the vessels being closed. Fig. 60 2 shows a modified apparatus wherein both the vessels are open.

The apparatus represented in Fig. 1 consists of two closed treating vessels *a*, *b* placed on the same level, which may suitably be 65 provided with strainers on their floors, and are connected by the pipes *c*, *d* with two of the nozzles of a four-way cock *e*, for reversing the direction of circulation of the treating liquid, the two other nozzles of this cock 70 being connected by the pipes *f*, *g* with a rotary pump *h*. The pipe *g* is connected with the feed pipe *i* for liquid and the suction nozzle *j* of the pump by a three-way cock *k*. Above, the vessels *a*, *b* are connected by two 75 pipes *m*, *n* with an intermediate vessel *o*, which is provided with a cock *p* for the exit of air and a steam heating coil *q* with a feed cock *r*. The pipes *m*, *n* are provided with cut off cocks *s*, *x*. In the treating vessel *b* 80 there is arranged an overflow pipe *t* which is provided with a valve *u* opening downward. For the vessel *a*, this arrangement is, for the sake of example, somewhat modified. In this case the overflow pipe *v* is connected 85 to the vessel *a* on the exterior, and it is also connected with the pipe *c* and similarly contains a retaining valve *w*. The object of this arrangement will be seen from the following description.

The apparatus is made use of in the following manner: After the vessels *a*, *b* have been charged with the material to be treated the air must first be expelled from the apparatus. The pump is fed through the pipe *i* 95 with the liquid to be used, which in the position of the four-way cock *e* shown in the drawing is forced into the vessel *a* by the pump through the pipes *f*, *c*, flows through the material contained in the vessel *a* and fills the latter, at the same time driving out the air, which escapes through the opened air-exit cock *p*. Finally the liquid passes over into the vessel *o*, which it fills to a certain degree, the cock *x* being closed, so that the vessel *o* contains nearly as much liquid as would be necessary for the treatment of the material in the vessel *b*. At this moment the admission of liquid through the pipe *i* is interrupted by turning the three- 100 105 110

way cock *k* in the direction of the arrow. By this means there has been admitted into the apparatus, in spite of the presence of two treating vessels scarcely more liquid than corresponds to the amount of material to be treated in a single vessel. By turning the cock *k*, the cock *a* being opened, the pipes *g*, *d* are brought into connection with the suction nozzle *j* of the pump, and a movement of circulation of the liquid takes place in such a way that the liquid, if the material in the vessel *b* is sufficiently penetrable, is drawn through the latter. If, on the contrary, the material offers a certain resistance to the percolation of the liquid, the liquid which passes through the pipe *n* into the vessel *b* accumulates above the material and finally flows through the overflow pipe *t*, the valve *u* of which is open, directly toward the pipe *d* and to the pump, so that the feeding of the latter is not affected by the impenetrability of the material in the vessel *b*. After the movement of circulation of the liquid has been thus brought about the latter is heated by means of the steam heating coil *g*. As the liquid begins to boil the cock *s* in the pipe *m* is closed, and the four-way cock *e* is turned through 90° in order to reverse the course of the liquid. The vessel *a* empties itself of liquid while the liquid in the vessel *b* rises, penetrates the material in the latter, the valve *u* being closed automatically, and at the same time the liquid forces any air which may still remain in the vessel through the cock *p*. The liquid finally reaches the pipes *n*, *m*, when the cock *s* is again opened and a similar movement of circulation of the liquid set up as before, but with the difference that it now takes place in the contrary direction. The parts of the apparatus are now empty of air. The heating of the liquid is continued, and it is then only necessary to reverse from time to time the four-way cock *e*, first in one direction and then in the other, in order to carry out the proper working of the apparatus. As a matter of fact in one working position of the four-way cock *e*, for example that shown in the drawing, the material in the vessel *a* is steeped or impregnated in full bath by pressure action by the liquid supplied by the pump, while at the same time the liquid from the lower part of the vessel *b* is sucked away to drain the material therein and the amount of liquid which passes over into the vessel *b* percolates by a kind of dripping or filtering action through the material in this vessel, if it be sufficiently penetrable, to carry away the impurities dissolved in the full bath, but if the charge be insufficiently penetrable the liquid is able to run off immediately through the overflow pipe *t* whence it collects in the lower part of the vessel *b* and serves for feeding the pump. If the four-way cock *e* be moved through

90° the vessels *a* and *b* exchange their functions, in so far as that then the vessel *b* serves for the treatment in the full bath, of its contents drained during the preceding phase, and the vessel *a* for the treatment of its contents in the dripping or filtering process.

From what has been said it follows in the first place that here, by working with two vessels for the material at the same time, the process can be carried out with much less liquid than was formerly required, that is to say, that scarcely more liquid is required than would be necessary for treating the material in one of the vessels. From this there results considerable economy in liquid, and, in correspondence therewith, in fuel also in order to bring the former to the temperature desired. It is also to be remarked, however, with reference to the chemicals that since, as the result of the presence of a smaller quantity of liquid they are less diluted, and can be more completely used up, while a more rapid action is obtained as the result of greater concentration, there naturally results economy in chemicals and time.

The apparatus shown in Fig. 2 differs from that above described in so far as the two treatment vessels *a*, *b* are open and are directly connected below their upper edge to one another by the pipes *m*¹, *n*¹ and the intermediate vessel *o*¹ which obviously may also be omitted.

What I claim is:

1. Apparatus for boiling and bleaching textile materials, comprising two treating vessels each adapted to be charged with textile material to be treated by a liquid, a pump for maintaining said liquid in a circulating motion, pipe connections between said pump and the lower part of said vessel, means for reversing the direction of flow of the liquid through the vessels; an upper intermediate heating vessel placed between the said treating vessels, having pipes leading to the upper part of each of said vessels connecting the upper parts of said vessels through said intermediate vessel, and means connected in the same circuit with said pump and reversing means for the initial supply of liquid to the vessels from below in view of expelling air from the textile material therein, substantially as and for the purpose described.

2. Apparatus for boiling and bleaching textile materials, comprising two closed treating vessels each adapted to be charged with textile material to be treated by a liquid, a pump for maintaining said liquid in a circulating motion, pipe connections between said pump and the lower part of said vessels, means for reversing the direction of flow of the liquid through the vessels, an upper intermediate vessel placed between

the said treating vessels, a heating device for heating the liquid in said intermediate vessel, pipes connecting said intermediate vessel with the upper part of the treating vessels and closing means in said pipes for temporarily cutting off the connection between said intermediate vessel and the treating vessels when the apparatus is to be supplied with liquid and the air to be expelled therefrom, substantially as and for the purpose described.

3. Apparatus for boiling and bleaching textile materials, comprising two closed treating vessels each adapted to be charged 15 with textile material to be treated by a liquid, a pump for maintaining said liquid in a circulating motion, pipe connections between said pump and the lower part of said vessels, means for reversing the direction of 20 flow of the liquid through the vessels, an upper intermediate vessel placed between the said treating vessels, a heating device for heating the liquid in said intermediate vessel, pipes connecting said intermediate 25 vessel with the upper part of the treating vessels, closing means in said pipes for temporarily cutting off the connection between said intermediate vessel and the treating vessels when the apparatus is to be supplied 30 with liquid and the air to be expelled therefrom, and means connected in the same circuit with said pump and reversing means for the initial supply of liquid to the vessels from below in view of expelling air from the 35 latter and the textile material therein, substantially as and for the purpose described.

4. Apparatus for boiling and bleaching textile materials, comprising two treating vessels each adapted to be charged with textile material to be treated by a liquid, a 40 pump for maintaining said liquid in a circulating motion, connections between said pump and the lower part of said vessels, means for reversing the direction of flow of the liquid through the vessels, and an upper 45 intermediate vessel, placed between the said treating vessels, connected with the upper part thereof and designed to receive the excess of liquid from the full bath operation of one of the treating vessels for the simultaneous dripping or filtering operation in the other vessel, the said two treating vessels being provided with overflow pipes and these again with retaining valves so that for the period of raised pressure in the one vessel the corresponding overflow pipe has its retaining valve closed, while at the same time for the period of reduced pressure in the other vessel the retaining valve belonging to it is opened, in order that the excess 50 of liquid which accumulates in the latter vessel through the inadequate penetration of the material may flow off through the corresponding overflow pipe, substantially as hereinbefore described. 55

In witness whereof, I have hereunto signed my name in the presence of two subscribing witnesses.
